UNITED STATES PATENT OFFICE.

STEPHEN S. CONWAY, OF CHICAGO, ILLINOIS, ASSIGNOR TO ARMOUR & CO., OF SAME PLACE.

DESIGN FOR A MEAT-CAN.

SPECIFICATION forming part of Design No. 28,989, dated July 5, 1898.

Application filed February 21, 1898. Serial No. 671,204. Term of patent 7 years.

To all whom it may concern:

Be it known that I, STEPHEN S. CONWAY, citizen of the United States, residing at Chicago, in the county of Cook and State of Illinois, have invented and produced a new and original Design for Meat-Cans, of which the following is a specification, reference being had to the accompanying drawings, forming part thereof, in which—

Figure 1 is a perspective view of a meat-can of my improved design. Fig. 2 is a plan view thereof, and Fig. 3 is a central longitudinal sectional view.

The leading feature of my improved design consists in a can or box the body of which has the shape of a semi-ellipse or the half of an ellipse divided at its minor axis, and having the corners rounded where the straight side joins the curve.

In the said drawings, A indicates the top 20 of the can, B the bottom thereof, and C the body thereof. This body has the shape for the greater portion of its extent of one-half of a flattened ellipse, the remainder of the body being formed by a straight side D co- 25 incident with the minor axis of the ellipse and being joined to the curved portion of the body by rounded portions E.

I claim—

The design for a meat-can, as herein shown 30 and described.

STEPHEN S. CONWAY.
